APPARATUS FOR THE CONTROL OF
HIGHWAY CROSSING SIGNALSStanley E. Gillespie, Evanston, Ill., assignor to
Western Railroad Supply Company, Chicago,
Ill., a corporation of Delaware

Application January 28, 1944, Serial No. 520,042

3 Claims. (Cl. 246—130)

My invention relates to apparatus for the control of highway crossing signals, and more particularly to control apparatus that provides a substantially uniform warning period of the signal prior to the arrival of the train at the intersection regardless of the speed of the train.

A highway crossing signal is customarily controlled through an approach or operating track section which is of a length sufficient to provide a given warning period, usually 20 seconds, of the signal prior to the arrival of the train at the intersection when the train is traveling at the maximum permissible speed for all trains. The introduction of high speed trains has required that such operating section be increased in length, with the result that the warning period of the signal for a slow train may be so long as to be annoying to the highway users. This condition has created a demand for more uniform time control of highway crossing signals. A uniform time control can be accomplished by delaying the starting of the warning operation of the signal when a slow train enters the operating section, the interval of delay being for a duration which depends upon the speed of the train. Such a time control requires that the control apparatus includes means along the trackway to determine the train speed, and means to delay the starting of the warning operation of the highway crossing signal for an interval made variable according to the speed.

Accordingly, a feature of my invention is the provision of novel and improved uniform time control apparatus for highway crossing signals.

Another feature of my invention is the provision of highway crossing signal control apparatus incorporating novel and improved means by which the speed of a train approaching a highway intersection is determined and the warning operation of the highway crossing signal is delayed after such train reaches a fixed point for an interval the duration of which is varied according to the speed.

Still another feature of my invention is the provision of highway crossing signal control apparatus incorporating novel means to introduce a preselected time interval at the first part of the time occupancy of a train in a speed measuring section and to reverse this sequence in the time occupancy of a train in an operating section.

Again, a feature of my invention is the provision of novel motor operating means for moving a circuit contact actuating member away from a starting position at a uniform rate during the interval consumed by a vehicle in traveling

through a preselected fixed distance of its trackway and then to subsequently restore such contact actuating member to its starting position at the same or at a different uniform rate, a contact being actuated by this member during a preselected portion of its travel.

Other features, objects and advantages of apparatus embodying my invention will appear as the specification progresses.

10 The foregoing features, advantages and objects embodying my invention I accomplish by forming the track on the approach side of the intersection into consecutive track circuited sections of preselected lengths and by providing a motor operated time measuring means which is governed by these track circuits to move a contact actuating member at a uniform rate away from a starting position during the time interval consumed by a train in traveling the most remote and speed measuring track section and then reversing the movement of the contact actuating member and restoring it at a uniform rate back to its starting position when the train enters the second and operating track section. 20 This contact actuating member is made to close a contact when moved a predetermined distance from its starting position, such distance representing a time interval equal to the warning period prescribed for the highway crossing signal, and which period is usually taken as twenty seconds. The speed measuring section is made a length equivalent to that required to drive the contact actuating member just short of the position where the contact is closed when the train is traveling at the maximum permissible speed. Thus the contact is not closed for a train operating at the maximum speed but is closed for an interval for a slower train, the interval the contact is closed being inversely proportional to the speed of the train. Also the contact remains closed during the return movement until the predetermined position of the contact actuating member is reached, and consequently, the interval the contact remains closed subsequent to the train entering the operating section is inversely proportional to the speed of the train. This contact is interposed in the control circuit network for the highway crossing signal, the arrangement being such that the warning operation of the signal is started when a train enters the operating section unless the contact of the time measuring means is closed, and if such contact is closed, the warning period is held in abeyance until such time as the contact is opened. 30 It follows that for a train moving at the maxi-

mum speed, the warning operation of the signal is started when a train enters the operating section, but that for a slower train the starting of the warning operation of the signal is delayed for an interval, the duration of such interval being inversely proportional to the train speed.

The entrance end of the operating section is located from the intersection a distance equal to that traveled by a maximum speed train in the prescribed warning period of the signal. With proper proportioning of the parts, the delay brought about through the time measuring means is such that the warning period of the signal is uniform for all speeds within a relatively wide range of speeds.

The operating section may be subdivided with a third or positive operating section adjacent the intersection, and for which latter section the signal is operated even if the train is not moving. This third or positive operating section I preferably make of a length sufficient to provide the preselected warning operation of the signal for a train moving at the minimum speed of the preselected range of speeds for which a uniform operating period is to be effected.

The time measuring means preferably comprises two motors, a differential beveled gear set and a drum having mounted on its outer surface contact actuating members. This drum is mounted on the cage portion of the differential beveled gear set. A first one of the two motors is connected to a first drive gear of the set and the second motor is connected to a second drive gear of the set. The two driven gears of the set are journaled in the drum. Energization of the first motor with the second motor held stationary rotates the drum in one direction, and energization of the second motor with the first motor held stationary rotates the drum in the opposite direction. The first motor is used to rotate the drum from a starting position toward an extreme position which is a little less than one revolution, and the second motor is used to drive the drum from whatever position it has advanced toward the extreme position back to the starting position. By using different gear ratios the rate at which the drum is rotated in one direction can be made different from that at which it is rotated in the other direction, and I preferably arrange the parts so that the drum is driven from the starting position toward the extreme position at a relatively fast rate compared to the rate at which it is driven back toward the starting position. On the outer surface of this drum are formed three cam segments each of which serves as a contact actuating member. One of these cam segments is used to close the contact interposed in the control network for the highway crossing signal and it is formed so as to close the contact a preselected number of degrees away from the starting position and thereafter retain it closed. The other two cam segments are used to operate contacts interposed in the motor operating circuits so that the motor operating circuit for the first motor is opened at the extreme position and the motor operating circuit for the second motor is opened at the starting position. A check contact is preferably provided in the time measuring means to check its operating condition.

I shall describe two forms of apparatus embodying my invention, and shall then point out the novel features thereof in claims.

In the accompanying drawing, Fig. 1 is a diagrammatic view showing one form of apparatus

embodiment of my invention. Fig. 2 is a view taken on the line II-II of the motor driven differential beveled gear set of the time measuring means of Fig. 1. Fig. 3 is a diagrammatic view showing a second form of apparatus embodying my invention, and Fig. 4 is a view showing the construction of the motor for the time measuring means of Fig. 3.

In each of the several views like reference characters are used to designate similar parts.

Referring to Fig. 1, the reference characters 1a and 1b designate the rails of a stretch of railway over which traffic normally moves in the direction indicated by an arrow, and which railway is intersected by a highway H, a highway crossing signal S being located at the intersection. Signal S may be any one of the standard forms of highway crossing signals, such as a barrier, a gate, flashing lights or a bell, or it may consist of a combination of such devices, and in Fig. 1, the signal S is shown as an audible signal in the form of an electric bell.

The rails 1a and 1b on the approach side of the intersection, that is, on the left-hand side as viewed in Fig. 1, are formed by insulated rail joints into three track sections D-E, E-F and F-G; and over which track sections a train travels in the order named in approaching the intersection. As an aid in understanding the apparatus, I shall refer to section D-E as a speed measuring section, section E-F as an operating section and section F-G as a positive operating section. The lengths of these track sections are made to agree with the maximum permissible speed for all trains and with a preselected warning period of the signal S prior to the arrival of a train at the intersection. By way of illustration, I shall assume that the maximum permissible train speed is 120 miles per hour or 176 feet per second, and a 20 second warning period of the highway crossing signal prior to the arrival of the train at the intersection is required. I shall further assume that the warning period of 20 seconds is to be substantially uniform for all train speeds between the maximum speed of 120 miles per hour and a preselected minimum speed of 30 miles per hour or 44 feet per second. It is to be understood of course that the invention is not limited to such speeds and warning period, and other speed limits and warning periods can be used. Under the circumstances herein assumed, the entrance end E of the operating section is made approximately 3520 feet from the intersection, 3520 feet being the distance traveled by a train moving at the maximum speed in the prescribed warning period (176×20). Preferably the section F-G adjacent the intersection is made of a length equal to that traveled by a train moving at the preselected minimum speed in the 20 second warning period and in this instance the section F-G is approximately 880 feet in length (44×20). The speed measuring section D-E is of a length equal to that traveled by a train moving at the maximum speed in some preselected interval. Preferably this selected interval is made relatively short so that the speed measuring section D-E can be correspondingly short, and I shall assume that the section is 1760 feet in length so that a train moving at the maximum speed of 176 feet per second requires ten seconds to advance therethrough.

Each of these track sections is equipped with a track circuit including a source of current such as a battery 2 connected across the rails at one end of the section, and a relay designated R plus

a prefix corresponding to the location connected across the rails at the other end of the section. These track circuits govern the signal S through a time measuring means designated as a whole by the reference character TM and a control relay CR.

The time measuring means TM comprises two motors M₁ and M₂, a differential beveled gear set DG and a drum DD on the outer surface of which drum contact actuating members are formed. In Fig. 1 the motors M₁ and M₂ are alike and are constant speed direct current motors supplied with power from any convenient source of direct current such as a battery the terminals of which are indicated at B and C. While direct current motors are shown, it is to be understood that constant speed alternating current motors, such as synchronous motors, may be used.

The differential beveled gear set DG comprises four gears 4, 5, 6 and 7. Gears 6 and 7 are driven gears mounted on shafts 8 and 9, respectively, and which shafts are journaled in a drum DD. Gears 4 and 5 are drive gears, gear 4 being fixed on a shaft 11, journaled at 10, and gear 5 being fixed on a shaft 11a, journaled at 12. Motor M₁ is connected to shaft 11 through a motor shaft indicated by a dotted line 13 and a worm gear 14, and motor M₂ is connected to shaft 11a through a motor shaft 18, a gear train 17, a shaft 16 and worm gear 15. It is apparent that with gear 5 held stationary and gear 4 rotated, the driven gears 6 and 7 will travel around the gears 4 and 5 causing the drum DD to be rotated, and with gear 4 held stationary and gear 5 rotated, the two gears 6 and 7 are also driven around gears 4 and 5 causing drum DD to be rotated. By proper selection of the direction of operation of the motors, the drum DD is made to rotate counterclockwise as viewed in Fig. 2 when gear 4 is driven by motor M₁ and is rotated clockwise when gear 5 is rotated through motor M₂. As will appear hereinafter, the drum DD is normally positioned at a starting or normal position, and is rotatable through a movement of a little less than one revolution to an extreme position when gear 4 is the driving gear and drum DD is rotated back to the starting position when gear 5 is the driving gear. To agree with the herein assumed lengths of the track sections and with the herein assumed warning period for signal S, the rate of rotation of drum DD by gear 4 is preferably twice the rate of rotation of the drum when driven by gear 5.

The outer surface of the drum DD is formed with three cam segments positioned on the lines a, b and c, respectively, and each of which cam segments serves as a contact actuating member. For the sake of clarity, these three cam segments 19, 20 and 21 are illustrated in Fig. 1 on separate circles of the surface of the drum DD so that their cooperation with associated contacts can be clearly shown. These contact actuating members and their associated contacts are shown in Fig. 1 at their respective positions for the starting position of the time measuring means. The function of these different contacts and contact actuating members of the time measuring means will appear when the operation of the apparatus is described.

Control relay CR is energized through a circuit network controlled by the track relays ER and FR, and the time measuring means TM as will appear shortly. Relay CR in turn governs an obvious operating circuit for signal S, this

circuit being completed at back contact 22 of relay CR.

Normally, that is, when sections D—E, E—F and F—G are unoccupied, the time measuring means TM is at its starting position, that is, the position shown in Fig. 1, and control relay CR is energized causing signal S to be silent. The circuit path through which relay CR is normally energized can be traced from terminal B through front contact 23 of relay ER, front contact 24 of relay FR and winding of relay CR to terminal C.

I shall next assume that a train traveling at the maximum speed of 120 miles per hour approaches the intersection, and which train upon entering section D—E shunts track relay DR to complete a circuit for motor M₁, such motor operating circuit extending from terminal B through back contact 25 of relay DR, front contact 26 of relay ER, a normally closed contact 27—28 of the time measuring means, and motor M₁ to terminal C of the current source. Motor M₁ is now operated to drive the gear 4 and in turn to cause drum DD to be rotated counterclockwise at a rate preselected according to the rate of operation of motor M₁ and the proportioning of the gears. It is to be observed that as soon as the drum DD rotates away from its starting position, a contact 29—30 is closed due to cam segment 20 moving out from under the contact member 29 and allowing contact member 29 to spring into engagement with contact member 30. It has been assumed for illustration that section D—E is 1760 feet in length, and thus this train moving at the maximum speed, would travel the section in substantially 10 seconds. The parts of the time measuring means TM are proportioned so that ten seconds operation of motor M₁ rotates drum DD just short of the point where the cam segment 21 reaches a contact member 31 to raise contact member 31 into contact with a contact member 32 closing the circuit therethrough.

When this train enters section E—F, track relay ER is shunted to open front contacts 23, 26 and 38, and close back contact 33. The opening of front contact 26 opens the circuit for motor M₁ and that motor is deenergized and the counterclockwise rotation of drum DD is stopped. The closing of back contact 33 completes a motor operating circuit for motor M₂, such circuit extending from terminal B through back contact 33 of relay ER, contact 29—30 of the time measuring means, and which contact is now closed, and motor M₂ to terminal C. With motor M₂ operated, the drum DD is rotated clockwise back to its starting position, at which position the contact 29—30 is opened and motor M₂ is deenergized, leaving the time measuring means at its normal or starting position. The opening of front contact 23 of relay ER opens the circuit through which the relay CR is normally energized and since there is no other path now completed for relay CR, relay CR is released to close the signal operating circuit at back contact 22, and signal S is operated to provide a warning indication to the highway users. When the train advances to enter section F—G, track relay FR is shunted to open the circuit for relay CR at a second point. As explained hereinbefore the entrance end E of section E—F is located 3520 feet from the intersection, and consequently the bell of signal S is sounded approximately 20 seconds prior to the arrival of this train at the intersection. When this train vacates the different track sections, the corresponding track relays are reen-

ergized so that when the rear end of the train passes over the intersection to vacate section F—G, the relay CR is reenergized and the sounding of the bell of signal S ceases.

I shall next assume that a train traveling at 60 miles per hour approaches the intersection. This train upon entering section D—E shunts track relay DR and the motor operating circuit for motor M1 is completed so that the drum DD of the time measuring means is driven away from the starting position the same as in the previous case. This train consumes approximately 20 seconds in passing through the speed measuring section D—E and since, as explained hereinbefore, the contact 31—32 is closed ten seconds from the starting position, the contact 31—32 is closed during the last ten seconds of the operation of the drum in response to this train moving at 60 miles per hour. When this train enters section E—F, track relay ER is shunted to open the circuit for motor M1, close the circuit for motor M2 and open one path of the circuit network for relay CR, the same as explained for the previous train. Control relay CR is now supplied with current through a circuit path that extends from terminal B through contact 34—35 closed in a manner to appear shortly, contact 31—32 of the time measuring means and now closed due to the position of drum DD, front contact 24 of relay FR and winding of relay CR to terminal C, and the sounding of the bell of signal S is delayed after this train enters the section E—F. Since motor M2, gear train 17 and worm gear 15 are so proportioned that the drum DD is driven back toward its starting position at one-half the rate at which the motor M1 drove the drum away from the starting position, contact 31—32, which was closed for the last ten seconds of the operation of the drum away from the starting position remains closed for the first 20 seconds of the operation of the drum by motor M2 before the contact segment 21 is moved out from under the contact member 31 to allow that contact to spring out of engagement with contact member 32. That is to say, the warning operation of signal S is delayed for an interval of substantially 20 seconds subsequent to this train entering the section E—F. Since the point E is 3520 feet from the intersection, and the operation of signal S is delayed for 20 seconds after the train has passed the point E, it follows that this train moving at 60 miles per hour has advanced to a point 1760 feet from the intersection before the bell is sounded and a 20 seconds warning period of the signal S is effected.

Contact member 35 is attached through a linkage to a fly ball type of governor 36 driven from a shaft 37 of the gear train 17. This linkage and governor are proportioned for contact member 35 to be moved downward as viewed in Fig. 1 to engage contact 34 when motor M2 is operated at a rate at least equal to its normal rate. Consequently if motor M2 does not operate at its normal rate to bring the drum DD back to a point where contact member 31—32 is opened at the proper time, the circuit for relay CR is opened at contact 34—35 to cause immediate operation of the signal S.

I shall next assume a train traveling at 30 miles an hour approaches the intersection. This train consumes approximately 40 seconds in advancing through the speed measuring section D—E, and contact 31—32 is closed for the last thirty seconds of this 40 seconds period of operation. When this train enters section E—F to shunt track relay

ER, the motor M1 is stopped and the motor M2 is operated as explained hereinbefore. Also relay CR is retained energized through the circuit path including contact 31—32. It requires substantially 60 seconds of operation of motor M2 to drive drum DD back to the point where contact 31—32 is open. In 60 seconds this train advances approximately 2640 feet (44×60) from the entrance end E of section E—F, and thus it has arrived at the point F, which has been assumed to be 880 feet away from the intersection. That is to say, for a train moving at the minimum pre-selected speed of 30 miles per hour, the circuit for the relay CR is opened at contact 31—32 of the time measuring means, and at front contact 24 of track relay FR at substantially the same moment. In any event the 20 seconds warning period of the signal S is obtained for the train moving at the 30 mile per hour speed.

From the foregoing discussion it is apparent that the apparatus of Fig. 1 operates to effect a substantially 20 seconds warning operation of signal S for any train speed between the maximum speed of 120 miles per hour, and the minimum preselected speed of 30 miles per hour.

A train moving at a speed less than 30 miles per hour may consume in advancing through section D—E, a time interval sufficient for motor M1 to drive drum DD to its extreme position, and if so, cam segment 19 raises contact member 27 to open contact 27—38 and deenergize motor M1 stopping the movement of the drum at the extreme position. Under such circumstances, motor M2 would not likely be operated long enough to restore the drum to the point where contact 31—32 is opened while the train is advancing through section E—F, and thus no operation of the signal S would be effected for this train while it occupies section E—F. However, when any such slow moving train enters section F—G shunting track relay FR to open front contact 24, the control circuit for relay CR is opened and relay CR releases to initiate the operation of signal S irrespective of the position of the time measuring means. The operating period of signal S in this case would be somewhat longer than the usual 20 seconds, but since section F—G is relatively short, the train is visible to the highway users so that they can judge when it is safe to pass over the intersection.

It is to be pointed out that in case the drum DD has not been fully restored to its starting position before a train has vacated section E—F, an alternative motor operating circuit is completed at front contact 38 of relay ER and front contact 39 of relay DR and motor M2 is energized until the time measuring means is restored to its starting position. This last mentioned motor circuit is also effective to reset the time measuring means in case a train should enter the speed measuring section D—E and then reverse its direction and back out of section D—E.

From the foregoing description of the operation of the apparatus of Fig. 1, it is to be seen that the time measuring means is operable to determine the speed of the train and having determined the train speed to so delay the starting of the warning operation of signal S that a substantially uniform warning period obtains for all train speeds between the permissible maximum speed and the preselected minimum speed. In other words, the time measuring means is operable to interpose a preselected time interval which corresponds to the desired warning period of the highway crossing signal at the start in the time occupancy of a

train in the speed measuring section and to reverse this sequence in the time occupancy of the operating section.

Referring to Fig. 3, the apparatus is substantially the same as in Fig. 1, except for the time measuring means, and a description of the time measuring means only of Fig. 3 is required. In Fig. 3, the time measuring means TM1 comprises two motors M3 and M4, differential beveled gear set DG and drum DD. The construction of the beveled gear set DG and drum DD with its contact actuating members is the same as that of the time measuring means of Fig. 1, and this much of the time measuring means of Fig. 3 need not be again described.

The motors M3 and M4 are alike, and a description of one is sufficient for both. These motors are of the alternating current vibrating polarized armature type. Referring to motor M3 and looking at Figs. 3 and 4, two magnetizable cores 41 and 42 terminate in pole pieces 43 and 44, respectively, and have their other ends joined by a magnetizable backstrap 45. A permanent magnet 46 has one pole in contact with the backstrap and its opposite pole terminating in an enlarged pole piece (not shown) adjacent the pole pieces 43 and 44 of the electromagnet in the well-known arrangement. A polarized armature 47 is pivotally mounted at 50 in the enlarged pole piece of the permanent magnet, and is so disposed that its two ends are adjacent the pole pieces 43 and 44, respectively. Two windings 48 and 49 are mounted on the cores 41 and 42, respectively. These two windings 48 and 49 are connected to add their magnetizing effects and when current flows in one direction through the windings, the pole piece 43 is the north pole and the pole piece 44 is the south pole, with the result armature 47 pivoted in the permanent magnet 46 is attracted toward pole piece 43, and when current flows in the opposite direction in the two windings, pole piece 43 is the south pole and pole piece 44 is the north pole and armature 47 is caused to swing toward the pole piece 44. If an alternating current is supplied to the windings 48 and 49, the armature 47 is attracted toward the pole piece 43 each positive half cycle of the current, and is attracted toward the pole piece 44 each negative half cycle of the current. In other words, armature 47 vibrates at a rate corresponding to the frequency of the alternating current.

A ratchet pawl 51 is pivoted in a bracket member 52 secured to armature 47, bracket member 52 extending to one side of the armature for ratchet pawl 51 to operatively engage the teeth of a ratchet wheel 53 which is mounted on a shaft 54 to bring wheel 53 in a plane parallel to the cores 41 and 42. A retaining pawl 55 is mounted to cooperate with ratchet wheel 53 to permit only clockwise rotation as viewed in Fig. 4 of the wheel, such rotation being effected through the driving pawl 51 when operated due to the vibration of armature 47.

It is to be seen therefore that ratchet wheel 53 is advanced one tooth each swing of armature 47 so that the number of teeth the ratchet wheel is advanced each second corresponds to the frequency of the alternating current supplied to windings 48 and 49. The frequency of the alternating current used can be any suitable frequency within limits and such structure permits the use of alternating current of the commercial frequency of 60 cycles per second.

A pinion 56 is keyed to shaft 54 and meshes

with a gear 57 which is keyed to shaft 13 on which the worm wheel of the worm gear 14 is secured. Consequently when alternating current is supplied to windings 48 and 49 of motor 5 M3, the gear 4 of the differential gear set is driven at a substantially uniform rate, this rate being predetermined according to the frequency of the current and by the proportioning of the parts of the gears and the ratchet wheel.

10 Motor M4 is of similar construction and drives a ratchet wheel 58 keyed to a shaft 59 on which is secured a pinion 60 meshing with a gear 61 keyed to the shaft 16 which carries the worm wheel of worm gear 15. Thus motor M4 is operable to drive the gear 5 of the differential gear set at a rate predetermined by the frequency of the alternating current and by the proportioning of the gears and ratchet wheel.

15 It is readily to be seen therefore that the drum DD of the time measuring means TM1 can be made to rotate from its starting point toward its extreme position at a predetermined rate by the energization of motor M3, and can be made to rotate toward its starting position either at the same or at a different predetermined rate through the energization of motor M4.

20 Motors M3 and M4 are provided with operating circuits which correspond to the motor operating circuits for motors M1 and M2, respectively, of Fig. 1 except to be supplied with alternating current from a source having terminals BX and CX. The time measuring means TM1 is thus operable to control the contact 31-32 in response to trains operating in sections D-E and 25 E-F in substantially the same manner as the contact is governed by the time measuring means TM of Fig. 1.

25 In Fig. 3, the contact 31-32 of the time measuring means is used to control an alternating current relay CR1, a front contact 62 of which is included in the by-pass control circuit for the signal control relay CR. In this way the presence of the alternating current power used to energize motors M3 and M4 is checked, and a loss of such power removes the time measuring means TM1 from delaying the operation of the highway crossing signal S, signal S being then controlled through the track relays ER and FR.

30 The operation of the apparatus of Fig. 3 to determine the speed of a train and to control the starting of the warning operation of signal S so that a substantially uniform warning period obtains for all train speeds between the permissible maximum speed and the preselected minimum speed will be apparent from an inspection of Fig. 3 taken in connection with the description of the operation of the apparatus of Fig. 1.

35 Apparatus here disclosed has the advantages that the time measuring means is simple in construction, reliable in its operation and can readily be adjusted as to gear ratio and speed of operation, so that the apparatus can be applied and made to agree with the train speed prevailing at the specific location at which it is used. Also, a 40 commercial source of power may be used.

45 Although I have herein shown and described only two forms of apparatus for the control of highway crossing signals embodying my invention, it is understood that various changes and 50 modifications may be made therein within the scope of the appended claims without departing from the spirit and scope of my invention.

Having thus described my invention, what I claim is:

55 1. In time measuring means for highway cross-

ing signal control apparatus governed by a train for operating the signal a substantially uniform time period for all train speeds between preselected maximum and minimum speeds, the combination comprising, a drum mounted to be rotated a preselected portion of a revolution between a starting and an extreme position; a first, a second and a third contact actuating member formed on said drum to actuate a first, a second and a third contact respectively; said first contact to be opened only at said extreme position, said second contact to be opened only at said starting position, said third contact to be closed at a preselected point away from said starting position and thereafter retained closed to the extreme position, a differential bevel gear set having a driven gear mounted on a shaft disposed at right angles to the axis of the drum and secured in said drum to rotate the drum, a first motor connected to a first driving gear of said gear set and operable when energized to rotate said drum from the starting position toward said extreme position at a predetermined rate, a second motor connected to a second driving gear of said gear set and operable when energized to rotate the drum from the extreme position toward the starting position at a predetermined rate, said first contact included in an energizing circuit for said first motor, said second contact included in an energizing circuit for said second motor, and said third contact included in a highway crossing signal control circuit.

2. In time measuring means for highway crossing signal control apparatus governed by a train for operating the signal a substantially uniform time period for all train speeds between preselected maximum and minimum speeds, the combination comprising, a drum mounted to be rotated a preselected portion of a revolution between a starting and an extreme position; a first, a second and a third contact actuating member formed on said drum to actuate a first, a second and a third contact respectively; said first contact to be opened only at said extreme position, said second contact to be opened only at said starting position, said third contact to be closed at a preselected point away from said starting position and thereafter retained closed to the extreme position, a differential bevel gear set having a driven gear mounted on a shaft disposed at right angles to the axis of the drum and secured in said drum to rotate the drum, a first and a second motor means, each of said motor means including an alternating current magnet having a vibrating armature on which is carried a pawl that engages a ratchet wheel to rotate such wheel at a rate predetermined by the frequency of the alternating current, the ratchet wheel of said first motor means connected to a

first driving gear of said gear set to rotate said drum from the starting position toward said extreme position at a predetermined rate when that motor means is energized, the ratchet wheel of said second motor means connected to a second driving gear of said gear set to rotate said drum from the extreme position toward the starting position at a predetermined rate when that motor means is energized, said first contact included in an energizing circuit for said first motor means, said second contact included in an energizing circuit for said second motor means and said third contact included in a highway crossing signal control circuit.

3. In combination, a stretch of railway intersected by a highway and formed with a measuring and an operating track circuited section, a highway crossing signal at said intersection, a differential bevel gear set having a first and a second driving gear secured to a first and a second shaft respectively and a driven gear mounted on a third shaft and meshing with both of said driving gears, said first and second shaft in alignment, a drum mounted with its axis coinciding with the axis of said first and second shafts and having said third shaft secured therein, a first and a second contact actuating member formed on said drum to actuate a first and a second contact respectively, a first motor connected to said first shaft and operable when energized to rotate said drum in a first direction at a predetermined rate, a second motor connected to said second shaft and operable when energized to rotate the drum opposite to said first direction at a predetermined rate, a first circuit including a contact of the track relay of the measuring section and said first contact to energize said first motor, a second circuit including a contact of the track relay of the operating section and said second contact to energize said second motor, said first and second contacts disposed with respect to said first and second contact actuating members for said first motor to rotate the drum from a first position toward a second position until said second position which is less than one revolution is reached to measure the time consumed by a train in traveling the measuring section and for said second motor to rotate the drum back to the first position when the train enters the operating section, a third contact actuating member formed on the drum to operate a third contact at a preselected point between said first and second positions, and a control circuit for said signal having one branch including a contact of the track relay of the operating section and a second branch including said third contact.

STANLEY E. GILLESPIE.
